UNITED STATES PATENT OFFICE

HARRY J. HATER, OF CINCINNATI, OHIO

PISTON

Application filed July 9, 1928. Serial No. 291,427.

My invention relates to improvements in pistons for engines and more particularly to the type of pistons used in internal combustion engines or motors and having a head 5 and a skirt or tubular portion depending therefrom.

An important object of my invention is the provision of a piston which will fit snugly into its cylinder without danger of scoring, which will not slap or rattle and which 10 will bear uniformly on the cylinder.

A further object of my invention is to provide a piston of high expansion alloy which will have an unbroken major thrust 15 portion to insure strength and heat radiation to the skirt.

Another object of my invention is the provision of a piston with means for diverting radiation of heat from the head of the 20 piston.

Other objects and advantages of my invention will be apparent during the course of the following description.

In the accompanying drawings which 25 form a part of this specification and wherein like characters of reference denote like or corresponding parts throughout the same.

Figure 1 is a side elevation of a piston embodying my invention,

30 Figure 2 is an elevation taken at right angles to Figure 1,

Figure 3 is a central longitudinal sectional view taken at right angles to the plane of the piston pin openings,

35 Figure 4 is a similar view taken through the center of the piston pin openings,

Figure 5 is a horizontal sectional view taken on the line 5-5 of Figure 3 looking in the direction of the arrows,

40 Figure 6 is a similar view taken on the line 6-6 of Figure 4,

Figure 7 is a bottom plan view of my improved piston,

Figure 8 is a development thereof, and

45 Figure 9 is a side elevation of another form of my invention.

In the drawings, wherein for the purpose of illustration is shown a preferred form of my invention the numeral 10 designates the 50 solid head of the piston having the usual

packing ring grooves 11 and a depending hollow skirt 12. The skirt 12 is provided with the usual piston pin openings 13 which are preferably arranged in the center of the piston as shown. The wrist pin bosses 14 55 are each connected to the head of the skirt by a pair of substantially vertically arranged fins 15 arranged at a tangent to the piston pin bosses as shown in Figure 3 and extending to the inner edge of the bosses and to 60 the top of the piston as shown in Figure 4.

Transverse openings or slots 16 underlie the piston pin openings and are spaced a substantial distance above the bottom of the piston to leave a bearing surface 17 of sufficient width. The portions of the piston walls surrounding the piston pin openings are cut away or relieved as at 18, the relieved portions extending from the openings 16 to a point just below the lower 70 or oil ring groove, leaving an unrelieved band 19 between the oil ring groove and the relief 18.

A pair of downwardly extending slots 20 75 are arranged parallel to and on the edge of the reliefs on the minor thrust side of the piston. The slots 20 extend from a point immediately below the oil ring groove to a point below the top of the piston pin openings and are connected adjacent their upper ends by a transverse slot 21 which separates the head of the piston from the minor thrust side of the piston. A slot 22 is slightly inclined from the vertical and extends from the lower end of the piston skirt to a point 85 above the lower ends of the slots 20 and substantially equidistant from said slots. The walls of the slots 20 adjacent the reliefs 18 are preferably flared outwardly as shown.

It will be seen that I have provided a piston, the major thrust portion of which is unbroken and not separated from the head, allowing uniform heat radiation to the cylinder wall and giving a rigid non-collapsible portion to support the thrust loads subjected to it by the force of the explosion on the piston head. The openings 20 on the minor thrust portion serve to divert the heat flow from the head to the central part 90 of the skirt and cooperate with the trans- 100

verse slit and nearly vertical slit to control expansion by cutting off heat radiation to the portion below the transverse slit.

It will be seen that by this construction the skirt is connected to the head for at least three-quarters of its length.

The nearly vertical slit may have its angle to the vertical varied providing that it is not made vertical or does not effect the strength of the non-thrust side of the piston. The transverse openings 16 are centered beneath the piston pin openings and their length may be varied, although I have illustrated them as being of the same length as the lower portions of the relief. These openings break the heat transfer from the relatively heavy boss section to the lower bearing portion of the skirt, and this break in the connection of the boss section and the skirt gives resiliency to the lower end of the skirt, thereby assisting in the control of expansion and contraction of this part of the skirt. It will be seen that an annular bearing surface is provided at the lower end of the skirt which is unbroken except for the nearly vertical slit 22.

In Figure 9 I have illustrated the relief 18' as keystone in shape and the ends of the transverse openings 16' are arranged parallel with the inclined edges of the reliefs. The openings 20' are arranged with one side parallel with the edge of the relief and with the other side slightly inclined from the vertical in the opposite direction. The ends of the openings 16' and one side of the openings 20' may form continuations of the edge of the keystone relief. The other features of the piston correspond with that shown in Figures 1 to 8.

While I have shown and described the preferred embodiment of my invention, it is to be understood that various changes in the size, shape and arrangement of parts may be resorted to without departing from the spirit of my invention or the scope of the subjoined claims.

Having thus described my invention, what I claim and desire to protect by Letters Patent is:

50 1. A piston comprising a head and a depending skirt, said skirt having a pair of piston pin openings with relieved areas therearound, a transverse opening underlying each piston pin opening and extending into said relieved area, said transverse opening being spaced a substantial distance from the bottom of the skirt to provide a substantially continuous bearing surface adjacent the lower end of the skirt, said skirt having a pair of slots extending along the edge of the relieved areas from a point immediately below the head of the piston to a point below the tops of the piston pin openings on the minor thrust side of the skirt.

65 2. A piston comprising a head and a de-

pending skirt, said skirt having a pair of piston pin openings with relieved areas therearound, a transverse opening underlying each piston pin opening and extending into said relieved area, said transverse opening being spaced a substantial distance from the bottom of the skirt to provide a substantially continuous bearing surface adjacent the lower end of the skirt, said skirt having a pair of slots extending along the edge of the relieved areas from a point immediately below the head of the piston to a point below the tops of the piston pin openings on the minor thrust side of the skirt, there being a transverse slit connecting the slots and separating the head of the piston from the portion of the skirt between the slots.

3. A piston comprising a head and a depending skirt, said skirt having a pair of piston pin openings with relieved areas therearound, a transverse opening underlying each piston pin opening and extending into said relieved area, said transverse opening being spaced a substantial distance from the bottom of the skirt to provide a substantially continuous bearing surface adjacent the lower end of the skirt, said skirt having a pair of slots extending along the edge of the relieved areas from a point immediately below the head of the piston to a point below the tops of the piston pin openings on the minor thrust side of the skirt, there being a transverse slit connecting the slots and separating the head of the piston from the portion of the skirt between the slots, said minor thrust portion of the piston skirt being provided with an inclined slit extending in a generally vertical direction from the lower end of the skirt to a point above the lower ends of the slits and below the transverse slit whereby the head of the piston is connected to the skirt for at least three quarters of its circumference.

4. A piston comprising a head and a depending skirt, said skirt having a pair of piston pin openings with keystone reliefs arranged therearound, there being a transverse opening underlying each piston pin opening and extending into said relieved area, the end walls of the opening being parallel to the inclined edges of the relief and forming a continuation thereof, said transverse openings being spaced a substantial distance from the bottom of the piston skirt, said skirt having a pair of slots extending along the edges of the relieved areas on the minor thrust side of the piston skirt, one of the sides of each slot forming a continuation of the edge of the relief.

5. A piston comprising a head and a depending skirt, said skirt having a pair of piston pin openings with keystone reliefs arranged therearound, there being a transverse opening underlying each piston pin

opening and extending into said relieved area, the end walls of the opening being parallel to the inclined edges of the relief and forming a continuation thereof, said transverse openings being spaced a substantial distance from the bottom of the piston skirt, said skirt having a pair of slots extending along the edges of the relieved areas on the minor thrust side of the piston skirt, one of the sides of each slot forming a continuation of the edge of the relief, there being a transverse slit connecting the slots and separating the head of the piston from the portion of the skirt between the slots.

15 6. A piston comprising a head and a depending skirt, said skirt having a pair of piston pin openings with keystone reliefs arranged therearound, there being a transverse opening underlying each piston pin opening and extending into said relieved area, the end walls of the opening being parallel to the inclined edges of the relief and forming a continuation thereof, said transverse openings being spaced a substantial distance from the bottom of the piston skirt, said skirt having a pair of slots extending along the edges of the relieved areas on the minor thrust side of the piston skirt, one of the sides of each slot forming a continuation of the edge of the relief, there being a transverse slit connecting the slots and separating the head of the piston from the portion of the skirt between the slots, said minor thrust side of the piston being provided with an inclined slit extending in a generally vertical direction from the lower end of the skirt to a point above the lower ends of the slots and below the transverse slit.

40 In testimony whereof I affix my signature.
HARRY J. HATER.
